TRAY OR SHELF SUPPORTING STRUCTURE

Robert V. Welhoefer, Waterloo, Wis.

Application March 18, 1952, Serial No. 277,125

4 Claims. (Cl. 248—243)

This invention relates to tray or shelf supporting structure and more particularly to the type of structure which permits selective vertically spaced positioning of the trays or shelves.

While numerous types of shelf supporting structures are in common use, the majority of these devices fail to provide the desired characteristics of combining ready adjustability with assurance of solid support for the shelf. One of the principal difficulties experienced with most devices of this type lies in the fact that the individual shelf supports are usually slidably positioned in holes with the result that frequent changing of their positions produces wear on the holes resulting in loose and insecure fitting.

While the present invention is adapted for a wide variety of uses for supporting shelves or trays, it is primarily intended for use in conjunction with display and sales counters and more particularly those used in bakeries and delicatessens wherein the foods are generally displayed on trays and which counters require frequent and thorough cleansing to insure against contamination of the foods.

The device of the present invention provides a shelf or tray supporting structure which is sturdy in construction and adapted to permit ready removal of the food containing trays and the tray supporting bars to clear the counter to facilitate its easy and thorough cleaning. The present tray supporting structure permits the rapid clearing, cleaning, and replacement of the food display trays with a minimum of effort and inconvenience.

The primary object of the present invention resides in the provision of a new and improved tray or shelf supporting structure including channel members adapted to adjustably position and retain tray supporting bars within the confines of the channel member to prevent their accidental displacement.

Another object of the invention resides in the provision in a shelf supporting structure of the combination with a channel member and a supporting block housed within said member in any of a plurality of selected spaced positions wherein it cooperates with the shelf to support the same and prevent relative movement between the channel and supported member.

Another object of the present invention resides in the particular formation of the supporting block which includes a central screw or bolt receiving hole having its opposite ends recessed for selectively receiving either the head of the screw or bolt or the nut which cooperates with the bolt to releasably retain the supporting block in position in the channel.

Another object of the present invention resides in the provision in a tray supporting structure of a channel member adapted to provide protection for the wall or partition of the counter against marring by preventing contact between the edge of the tray and the finished surface of the wall or partition.

Another object of the present invention resides in the

2

provision in a tray supporting structure of the combination of a channel member adapted to house a supporting block and the end of a tray supporting bar or tube in a manner to prevent the accidental displacement of the bar or tube from its tray supporting position.

Other objects and advantages will become apparent from the following description of an illustrative embodiment of the invention shown in the accompanying drawing.

10 In the drawing:

Figure 1 is a vertical transverse sectional view through a glass front display counter provided with a tray supporting structure embodying the teachings of the present invention;

Fig. 2 is an enlarged vertical longitudinal sectional view, taken on the line 2—2, showing the structural details of the present invention;

Fig. 3 is a vertical transverse sectional view, taken on the line 3—3 of Fig. 2 showing a portion of one of the channel members in elevation and showing the means for releasably retaining a tray bar supporting block in selected position of vertical adjustment within the channel member;

Fig. 4 is a vertical transverse sectional view, taken on the line 4—4 of Fig. 2 showing a portion of another of the channel members housing a supporting block in a manner similar to that shown in Fig. 3;

Fig. 5 is a horizontal transverse sectional view, taken on the line 5—5 of Fig. 4, showing a channel member in section and embracing a supporting block on which one end of a tray supporting bar or tube is adapted to rest within the confines of the channel member;

Fig. 6 is a perspective view of a supporting block and showing the nut receiving recess in one of its faces;

Fig. 7 is a view of a supporting block similar to that illustrated in Fig. 6 and showing a chamfered recess adapted to house the head of the anchoring means;

Fig. 8 is a view similar to that shown in Fig. 2 but being modified to the extent of having the respective channel members arranged in back-to-back contact with each other wherein the channel assembly provides the mounting means for the supporting structure on which the adjacent ends of separate shelves are supported; and

Fig. 9 is a horizontal sectional view taken on the line 9—9 of Fig. 8 and illustrating the use of saw cuts in the ends of the shelves for retaining them against lateral displacement with respect to the channel members.

Referring more particularly to Fig. 1 of the accompanying drawing, it will be noted that the illustrative embodiment of the present invention is shown applied to a glass front sales counter such as is commonly used in food stores such as bakeries, meat markets, and delicatessens for providing improved supporting means for food display trays arranged in tiers to more advantageously display the merchandise and to provide a tray supporting structure which may be partially dismantled to readily clear the counter of all cross members to facilitate the desired cleaning operation to maintain the counter in sanitary condition and add to the sales appeal of the merchandise displayed.

The shelf or tray supporting structure comprises a plurality of channel members 10 disposed in vertical arrangement and in laterally spaced relationship on each of the opposite ends of a counter section. It is to be understood that the cooperating pairs of channel members 10, disposed at opposite ends of the counter section lie in common vertical planes. The several channel members 10 may be individually secured in position upon either a partition member 11 of the counter or the inner surface of an end member 12 of the counter in any approved manner such as by the application of screws (not shown) applied in suitable spaced relationship through

any of a series of holes 13 disposed in uniform spaced relationship along the length of each channel member 10. It should be noted that the line of holes 13 are disposed midway between inwardly projecting flanges 14 of the channel members 10. As will hereinafter be more specifically described, the several holes 13 provide means for selectively positioning supporting blocks 15 in desired vertical spaced relationship within the channel members 10 to adjustably position the several display trays "T" in desired vertical spaced relationship within the display counter.

After the several channel members 10 have been properly secured in position, more particularly to the partition of the counter, it is desirable to pass a power drill through the aligned holes 13 in the channel members disposed on opposite sides of the partition 11 to form holes 16 therein adapted to receive anchoring means for releasably retaining the several supporting blocks 15 properly positioned within the channel members 10.

It should be noted at this time, referring more particularly to Figs. 6 and 7 that the several supporting blocks 15 each include a centrally disposed horizontal aperture 17 extending through the block 15. One end of the horizontal aperture 17 terminates in a flared or chamfered mouth 18; while the other end of the horizontal aperture 17 terminates in a nut-receiving recess 19.

Referring more particularly to the left hand portion of Fig. 2, it will be noted that a stove bolt 20 provides the anchoring means for releasably retaining a pair of supporting blocks 15 in selected position of vertical adjustment in the channel members 10 disposed on opposite sides of the partition 11. It should also be noted at this time that the supporting blocks 15 are applied within the channel members 10 in a manner such that the desired recess 18 or 19 lies outermost. After the selected elevation for any given tray support is chosen, a supporting block is applied to a stove bolt 20 by passing the same through the aperture 17 in the block 15 so that the head of the bolt will lie in the mouth 18 of the aperture 17; the end of the bolt 20 is then passed through the aligned holes 13 through the hole 16 in the partition 11 until its forward end is disposed within the channel 10 with the supporting block 15 on its head end disposed within the confines of its cooperating channel member 10. A similar supporting block 15 is then applied to the projecting end of the stove bolt 20 in a manner such that the nut-receiving recess 19 is outermost. A nut 21 is then applied to the end of the stove bolt 20 and is drawn into the recess by tightening the bolt 20 using a screw driver. In this way the supporting blocks 15 are releasably retained in tight position within their respective channel members 10. Referring more particularly to the right hand portion of Fig. 2, it will be noted that the supporting block 15 therein shown is secured in proper position by the application of a screw 22. Here again the chamfered recess 18 is outermost as the block 15 is applied between the flanges 14 of the channel member 10 so as to provide a flush seating for the head of the screw 22 which forms the anchoring means for the supporting block 15.

After the several supporting blocks 15 have been properly located and anchored in their respective channel members 10, care being taken that the individual supporting blocks of each set lie in a common horizontal plane, the several tray supporting rods or tubes 23 which are pre-cut to proper length whereby they may readily be positioned between opposite pairs of channel members 10 with their ends resting on the top surfaces of the aligned supporting blocks 15. The flanges 14 of each of the channel members 10 serve to retain the rods or tubes 23 against lateral displacement and at the same time, the flanges 14 of the several channels 10 afford adequate protection against contact between the edges of trays "T" and the wall 12 or partition 11 of the counter to thus avoid marking or marring of the interior finish of the counter.

The several rods or tubes 23 provide adequate support for the trays and also permit their easy positioning in and removal from the counter.

In the event that the supporting structure of the present invention is intended to be used as a shelf support, the rods or tubes 23 may be eliminated as indicated in Figs. 8 and 9 wherein shelves 24 are supported directly on the top surfaces of the supporting blocks 15. In instances where shelves 24 are mounted directly on the supporting blocks 15 suitable sawcuts 25 may be made in the ends of the shelves 24 to cooperate with the flanges 14 of the channel members 10 to prevent accidental displacement of the shelves on the supporting blocks 15 or to prevent relative lateral movement between the shelf and the channel members. Figs. 8 and 9 illustrate the use of pairs of channel members 10 arranged in back-to-back abutting relationship to serve as a partition between the ends of adjacent shelves.

From the foregoing detailed description of the present invention it will readily be understood that a simple and effective supporting structure has been provided for trays or shelves which permits the ready removal of the trays or shelves to permit the clearing of the counter or case to facilitate its easy cleaning and likewise the structure lends itself to quick reassembly so that the counter may be dressed with a minimum of effort.

The structure of the present invention also affords protection against the marring of the interior finish of the display counter through the operation of the flanges 14 on the channel members 10 which prevent contact between the edges of the trays and the wall of the counter.

Another marked advantage of the present shelf supporting structure resides in the fact that it is devoid of projecting portions and thus facilitates ready cleaning of the counter in a thorough manner without having the cleaning cloths or the hands caught upon sharp or projecting surfaces.

While the invention has been described in considerable detail in the foregoing specification, it is to be understood that various changes may be made in its embodiment without departing from or sacrificing any of the advantages hereinafter claimed.

I claim:

1. A tray or shelf supporting structure comprising a vertically disposed U-shaped channel member including a flat base portion provided with a series of vertically aligned spaced holes and a pair of parallel side flanges, a supporting block for reversible selective positioning between the side flanges of said channel member, said supporting block including one face adapted for contact with the base of said channel member, a pair of sides disposed adjacent said flanges to precluded rotary movement of said block in said channel, an aperture extending through said supporting block from front to rear thereof, a nut receiving recess at one extremity of said aperture, and a flared recess disposed at the opposite extremity of said aperture, and anchoring means being received through said aperture and a selected hole in the base of said channel member for releasably retaining said channel member and said supporting block in associated relationship.

2. A tray or shelf supporting structure comprising a vertically disposed U-shaped channel member including a flat base portion provided with a series of vertically aligned spaced holes and a pair of parallel side flanges, a supporting block for reversible selective positioning between the side flanges of said channel member, said supporting block including one face adapted for contact with the base of said channel member and a pair of sides disposed adjacent said flanges to precluded rotary movement of said block in said channel, an aperture extending through said supporting block from front to rear thereof, a square nut-receiving recess at one extremity of said aperture, a flared recess disposed at the opposite extremity of said aperture, and anchoring means comprising a nut and bolt, said bolt being received through said aperture

and a selected hole in the base of said channel member, and said nut being received in said square nut-receiving recess and contacting the sides thereof to preclude its rotation and releasably retain said supporting block in desired position of adjustment in said U-shaped channel member when said bolt is tightened.

3. A tray or shelf supporting structure comprising a vertically disposed U-shaped channel member including a flat base portion provided with a series of vertically aligned spaced holes and a pair of parallel side flanges, a supporting block for reversible selective positioning between the side flanges of said channel member, said supporting block including one face adapted for contact with the base of said channel member and a pair of sides disposed adjacent said flanges to precluded rotary movement of said block in said channel, an aperture extending through said supporting block from front to rear thereof, a nut receiving recess at one extremity of said aperture, and a flared recess disposed at the opposite extremity of said aperture, anchoring means comprising a threaded member being received through said aperture and a selected hole in the base portion of said channel, said threaded member having a head portion disposed in said flared recess in said supporting block, and a nut being received on said threaded member to releasably retain said channel member and said supporting block in associated relationship when said nut is tightened.

4. A tray or shelf supporting structure comprising a vertically disposed U-shaped channel member including a

flat base portion provided with a series of vertically aligned spaced holes and a pair of parallel side flanges, a supporting block for reversible selective positioning between the side flanges of said channel member, said supporting block including one face adapted for contact with the base of said channel member, a pair of sides disposed adjacent the flanges of said channel member, a top surface cooperating with said channel member to define a compartment to house a portion of a tray supporting bar or shelf to retain the same against lateral movement, an aperture extending through said supporting block from front to rear thereof, a nut receiving recess at one extremity of said aperture, and a flared recess disposed at the opposite extremity of said aperture, and anchoring means being received through said aperture and a selected hole in the base of said channel member for releasably retaining said channel member and said supporting block in associated relationship.
